UNITED STATES PATENT OFFICE

137,072

DESIGN FOR A TARGET GAME BOARD

Byron B. Baldwin, Centerline, Mich.

Application April 17, 1943, Serial No. 109,992

Term of patent 3½ years

To all whom it may concern:

Be it known that I, Byron B. Baldwin, a citizen of the United States, residing at Centerline, in the county of Macomb and State of Michigan, have invented a new, original, and ornamental Design for a Target Game Board, of which the following is a specification, reference being had to the accompanying drawing, forming a part thereof.

Fig. 1 is a front elevation of the target game board showing my new design.

Fig. 2 is a rear elevation thereof.

I claim:

The ornamental design for a target game board, as shown.

BYRON B. BALDWIN.
